UNITED STATES PATENT OFFICE

EDWARD KANTER AND EMIL FELDMAN, OF CLEVELAND HEIGHTS, OHIO

DESIGN FOR AN ARTICLE-DISPENSING MACHINE CASING

Application filed August 27, 1930. Serial No. 36,792. Term of patent 14 years.

To all whom it may concern:

Be it known that we, EDWARD KANTER and EMIL FELDMAN, citizens of the United States, residing at Cleveland Heights, in the county of Cuyahoga and State of Ohio, have invented a new, original, and ornamental Design for an Article-Dispensing Machine Casing, of which the following is a specification, reference being had to the accompanying drawing, forming part hereof, wherein the figure is a perspective view of the article dispensing machine casing, illustrating our new design.

We claim:

The ornamental design for an article dispensing machine casing, as shown.

EDWARD KANTER.
EMIL FELDMAN.
